UNITED STATES PATENT OFFICE

ROBERT H. SMILIE, OF OAKLAND, CALIFORNIA

RECONDITIONING DEVICE FOR TENNIS BALLS

Application filed September 7, 1927. Serial No. 218,093.

My invention relates to a device for reconditioning the surface of a tennis ball. Used tennis balls said to be "light" have lost in actual weight less than three per cent. They are smooth and their friction against the air has diminished causing them to be unsatisfactory in playing qualities. They act "light" and "sail" out of the court, but, as a matter of fact, the actual weight has not changed appreciably but rather the character of their surfaces. The restoration of the roughness of the surface and the white color of a tennis ball completely restores its playing qualities. The surface of all balls, if the fabric covering is not worn through to the rubber and which have not deteriorated from long disuse, is capable of being restored at a small cost. The purpose of a relatively rough surface on a tennis ball is two-fold, first, to provide the proper frictional engagement of the ball with the racket and second, to slightly increase the frictional resistance between the ball and the air as the ball passes through the air. The former is necessary in order that the ball may be given any desired twist or spin and the latter is necessary in order that the spin or twist given the ball may be effective in causing the ball to travel in a curved path. It is a well known fact that tennis balls, after they have been used for several sets by proficient tennis players are discarded because the nap or frictional surface of the ball has been worn smooth. The cost of a standard tennis ball is about fifty cents and three balls, as a rule, is the minimum number of balls used in a set of tennis, so that it can be readily seen that when three tennis balls are discarded at the end of two or three sets and new ones purchased, tennis becomes a rather expensive game.

The object of my invention is to provide a device which will recondition tennis balls, whose surfaces have been worn smooth by use, at a cost substantially less than their purchase price.

Another object of my invention is to provide a mechanism whereby a plurality of tennis balls may be made to pass over and 50 in contact with a plurality of teeth or picks

whereby a nap is raised by these picks on the entire surface of the balls.

Another object of my invention is to automatically raise a layer of nap on the surface of a plurality of balls and at the same 55 time work a chalk dust into the surface of the balls, thereby giving the balls so treated a new appearance.

A further object of my invention is to produce a motor driven mechanism comprising 60 a housing, means for producing a nap on the surface of the balls, means for chalking the balls, means for insuring that the balls take their proper course through said mechanism and means for taking care of the 65 use produced in the process.

The invention possesses other advantageous features, some of which with the foregoing will be set forth at length in the following description, where I shall outline 70 in full one form of the mechanism and process of my invention. In the drawings I have shown one embodiment of my invention but it is to be understood that the scope of my invention is to be limited only by my 75 claims and the prior art.

Referring to the drawings:

Figure 1 is a vertical mid-sectional view of my reconditioning device.

Figure 2 is a horizontal sectional view 80 taken on the line 2-2 of Fig. 1 and in the direction indicated by the arrows.

Figure 3 is a vertical section taken on the line 3-3 of Fig. 1 and taken in the direction as indicated by the arrows. 85

Figure 4 is a vertical section of the upper part of my mechanism taken on the line 4-4 of Fig. 1 and taken in the direction as indicated by the arrows.

Figure 5 is a diagrammatic representation 90 of the motion of a tennis ball as it comes in contact with the teeth or picking mechanism of my device.

My invention comprises a housing generally indicated as A, made up of a base 1, 95 sides 2 and 3, ends 4 and 5, and top 6. Secured within the housing and resting on the base 1, is a block or supporting member 7. The lower ends of a pair of spaced parallel and semi-cylindrically disposed tracks 8 and 100

9 are detachably secured to the block 7 by means of a plate 10 which is secured to the lower ends of the tracks 8 and 9 and which is slipped under the recess in the block 12. 5 The block 12 is secured to the block 7 by any suitable means such as screws or glue. The plate 10 also serves to hold the tracks 8 and 9 in spaced relation. The tracks 8 and 9 are made of a resilient material such as 10 leather and therefore can be curved into any desired form. In the embodiment shown in the drawings, they are resiliently held in contact with two series of semicircularly disposed pegs or pins 16 secured to 15 the sides 2 and 3 of the housing by means of a spring pressed arm 13. Arm 13 is shown fastened to the upper end of the tracks 8 and 9 by means of yoke 14. The yoke 14, like the plate 10, serves as a spacer 20 for the tracks 8 and 9. The arm 13 may be secured to the yoke 14 by any suitable means such as a rivet or welding. As shown in Figures 2, 3 and 4 the tracks 8 and 9 are trapezoidal in cross section. The inside 25 width of my housing is designed to be a little greater than the diameter of a standard tennis ball, and the dimensions of the tracks 8 and 9 are so chosen that when a ball is made to roll on said tracks the chord 30 determined by the two points of contact of the ball with the tracks 8 and 9 lies slightly above the lower surface of the ball as indicated in Fig. 3. The arm 13 passes through an aperture 17 in the end 4 and its outer 35 end is provided with an upturned portion 18. As best shown in Fig. 1, the arm 13 is urged inwardly by means of a spring 19, one end of which is suitably secured to the end of the housing A and the other end of 40 which is adjustably secured to portion 18 by means of an eye bolt and wing nut.

Wedged between the tracks 8 and 9 in semi-cylindrical disposition, is a needle belt 21. This needle belt comprises a flexible 45 support of leather or other suitable material in which has been placed at spaced intervals and at an angle, as best shown in Fig. 1, a plurality of inwardly projecting needles. I have found that phonograph needles form 50 a suitable and convenient needle for this purpose and may be secured to their support by any suitable means. The lower end of the needle belt is detachably held in a wedged position between the tracks 8 and 55 9 by means of an arm 22 whose inner and lower end is bifurcated to accommodate a pin or screw which is secured to the lower end of the needle belt. The other end of the arm 22 is secured to the end 4 by means 60 of a wood screw. At its upper end the needle belt is held in its wedged position by means of an arm 23 which projects through the aperture 17 and is provided at its outer end with downturned portion 24. The arm 65 23 is secured to the needle belt 21 by any

suitable means such as a rivet or screw and is urged inwardly by means of a spring 25, one end of which is secured to the end 4 and the other end of which is detachably secured to portion 24 by means of an eye bolt and wing nut.

In combination with the structure described above, I provide a drum 26, journaled by means of a suitable shaft and bearings to the sides 2 and 3 of the housing A. 75 This drum is concentrically journaled with respect to the cylindrically disposed tracks 8 and 9. The periphery of this drum is provided with a channel 27 as best shown in Figs. 2 and 3.

The design of my device and particularly the dimensions of the drum, tracks and width of the housing are such that a tennis ball will just be accommodated between the channeled drum and the two tracks 8 and 9 as best shown in Fig. 3. As shown in this figure, the ball is supported at four points, one on each track and one on each side of the channel in the drum. One reason for making the tracks 8 and 9 of leather, 85 is that leather is comparatively soft, and therefore the tennis balls as they are rolled along the tracks 8 and 9 by the drum 26 are not scarred or lined by the edges of the tracks. The shaft and bearings on which the drum 26 is journaled are provided with a suitable packing as shown in Fig. 2. One end of the shaft is slotted so that it may be readily keyed to an electric motor.

The upper side 6 of the housing A is provided with an opening 28 through which tennis balls, one at a time, may be passed. A cover 29 is provided to close this opening. An exit opening 30 is provided through the end 5. This exit opening is normally closed by means of a door 31 hingedly secured to the block 32. The block 32 is detachably secured to the block 7 by any suitable means such as guide members 33 and 39 fastened to the side walls 2 and 3. The upper edge of opening 30 is shouldered as at 33 to accommodate the upper end of the door 31. The door is normally held in its closed position by means of a spring actuated latch 34. The lower end of the portion 4 is provided with an opening 35 and the block 7 adjacent this opening is recessed or pocketed in order to accommodate a refuse container or basket 36. The contents of this basket may be emptied by means of the door 37 or by taking the 120 entire basket or container from its recess.

Strips of carpet 40 and 41, or of any other material having a rough surface are attached to the side members 2 and 3 as best shown in Figs. 1 and 2. The function of these strips 125 of carpet will be presently explained.

A triangularly shaped block 42 is fitted into the upper left hand corner of the housing A. The inner exposed face of this block, as indicated by the dotted line, is not perpen- 130

dicular with the planes of the sides 2 and 3.

A pinion 43, journaled on a pin 44 which in turn is secured to an arm 45, resiliently engages a reduced portion of the drum 26 and is driven thereby. The arm 45 is attached to the wall 2 by any suitable means such as a screw, and is urged in the direction of the shaft on which the drum 26 is journaled by gravity or by means of a spring 46, one end of which is attached to the arm 45 and the other end of which is attached to the wall 2.

The operation of my device is as follows: The cover 29 is lifted from the top 6 and one or more tennis balls are dropped into the housing through the opening 28. The force of gravity carries the balls to a position under the drum 26, at which position they are engaged by the drum 26 and are rolled along the tracks 8 and 9 by means of the drum 26 in a counterclockwise direction as viewed in Fig. 1. The motion of the tennis balls as they roll along the tracks 8 and 9 is best shown diagrammatically in Fig. 5. If a ball were to be rolled on the surface S in a clockwise direction as viewed in Fig. 5 the entire ball would rotate momentarily about an axis determined by the point of contact 47 of the ball with the surface S, with such a rotation every point of the ball momentarily moves slightly forward. The motion of a ball however when rolling along the tracks 8 and 9 is entirely different from the motion just described, for in my device the ball is supported at two points above the points 47 and therefore momentarily rotates about a chord 48 determined by the two points of contact of the ball with the tracks 8 and 9. All points of the ball below the chord 48 then move toward the left while all points of the ball above the chord 48 move toward the right. It will be noted that any point on the surface of a ball which rotates between the tracks 8 and 9 describes in general a looped epicycloidal path. The loop is due to the fact that the ball momentarily rotates about a chord rather than about a tangential line at the end of a radius of a ball. It is the backward and outward motion of such a point in executing the loop in the epicycloid that effects the picking action between the needle belt and the tennis ball. As the drum 26 is rotated in a counterclockwise direction the tennis ball is made to rotate in a clockwise direction which causes the center of the ball to travel in a counterclockwise direction. As the ball is rotated along the tracks 8 and 9, the tracks are slightly depressed. That portion of the ball which lies between the tracks is moved slightly backward and in so moving engages the needles of the needle belt 21, slightly depressing the needle belt as the ball advances. This depression of the tracks and the needle belt is made possible because of

the springs 19 and 25 and takes care of any inaccuracies in the setting of the needles in the needle belt. On further rotation of the ball the surface of the ball so engaged by the needle is moved slightly backward and away from the needles thereby producing a "picking action" on the surface of the ball. During the time that the ball is made to rotate over the entire length of the tracks 8 and 9, a narrow belt of nap has been raised along one of the great circles of the ball. On leaving the tracks 8 and 9 the ball possesses a clockwise spin, but on hitting the angularly disposed surface of the block 42 the direction of spin is changed. On passing between the strips 40 and 41 the ball is further rotated, by contact with these members, in a direction at right angles to the direction of its original spin. By the action of the block 42 and the strips 40 and 41, a new great circle or surface of the ball is presented to the action of the needle belt. At the time that the balls are inserted into my device some chalk or whitening is introduced into the machine and as the fibers of the surface of the ball are slightly raised due to the action of the needle belt, this whitening is worked into the entire fiber structure of the ball. By leaving the ball in my device three or four minutes the ball will have completed twenty or thirty cycles; every portion of the surface of the ball will have been exposed to the picking action of the needle belt and simultaneously the chalk or whitening has been worked into the fiber structure of the surface, thereby raising the nap on the entire surface of the ball and giving it a new appearance. The chalk is obviously reduced to a fine powder or is introduced into the housing in powdered condition. The fine powder becomes partly suspended in the air in the housing and also coats the surfaces with which the ball comes in contact.

When two or more balls are placed in my device at the same time, there may be a tendency for two of them, one above the other, to approach the tracks and driving drum of my device at the same time. It may happen that these balls may then assume a balanced position whereby there is a rotation of the balls with respect to each other, but no forward motion of either ball. To obviate this tendency I have provided the idler 43. As will be seen from the balls shown in dotted lines, the upper ball engages the idler 43 and has imparted to it a counterclockwise rotation. This counterclockwise rotation imparts a clockwise rotation to the lower ball and thereby causes the lower ball to move forward and the upper ball to ride over and back of the lower ball.

At the end of a period of three or four minutes the latch 34 may be released thereby permitting the door 31 to assume the position indicated in the dotted line, and as

the balls complete their last cycle they are thrown on the upper inclined portion of the door and roll out of the opening 30 into the hands of the operator.

5 The lint and excess chalk accumulated during the operation of the device is caught by the container 36 which may be emptied at the convenience of the operator.

10 The drum 26 may be operated by means of a suitable hand crank or may be power driven by means of any suitable motor.

I claim:

15 1. In a reconditioning device for tennis balls, a needle belt with which the tennis balls contact to raise a nap thereon, and means for simultaneously moving the centers of the balls in one direction and the surface of the balls in contact with said needle belt in the opposite direction.

20 2. In a reconditioning device for tennis balls, resiliently supported parallel tracks, a resiliently supported needle belt, means for rolling a tennis ball along said tracks in contact with said needle belt, to produce a nap on the balls, said tracks being so disposed that the chord joining the points of contact of said ball with said tracks lies between the center of said ball and its point of contact with said needle belt.

25 3. In a reconditioning device for tennis balls, means for supporting a tennis ball at the ends of a chord, a second means for rolling said ball along said supporting means and a third means in contact with said ball at the point of intersection of the perpendicular bisector of said chord with the surface of the ball nearest said chord, for producing a nap on the surface of said ball.

40 4. In a reconditioning device for tennis balls, means for simultaneously rotating a plurality of balls, means cooperating with said first means comprising a needle belt for producing a nap on the surface of the ball and a third means cooperating with said first means for preventing any two balls from becoming locked.

45 5. The process of reconditioning a tennis ball, consisting of raising the fibers of every portion of the surface of a ball, and simultaneously causing a chalk dust to be worked into the fibers so raised.

50 6. In a reconditioning device for tennis balls, picking means and automatic means for effecting a relative picking action between said picking means and a tennis ball whereby a nap is produced on the surface of the ball.

55 7. In a device of the character described means for moving a portion of the surface of a ball in the path of a looped epicycloid, and picking means arranged to engage the portion of said surface moving through the loop of the epicycloid to raise a nap on said surface.

60 8. In a device of the character described,

picking means for raising a nap on a tennis ball, and mechanical means for effecting repeated engagement between said picking means and the surface of the ball.

65 9. In a device of the character described, 70 a track, means for repeatedly traversing a tennis ball over said track, and means for picking the surface of the ball during each traverse over said track, thereby raising a nap on the ball.

75 10. In a device of the character described, 75 a track, means for traversing a tennis ball over said track, and means for picking a nap on the surface of the ball while traversing over the said track.

80 11. In a device of the character described, 80 a housing adapted to receive a tennis ball, picking means disposed in said housing, and means for repeatedly bringing the surface of a ball placed within the housing into contact with said picking means to raise a nap on the surface of the ball.

85 12. In a device of the character described, 90 a housing adapted to receive a tennis ball, picking means for raising a nap on a tennis means including a rotatable member within the housing for repeatedly bringing the surface of a tennis ball within the housing into contact with the picking means to raise a nap on the surface of the ball.

95 13. In a device of the character described, 95 picking means for raising a nap on a tennis ball, and mechanical means for repeatedly bringing different peripheral portions of a ball into picking contact with said means, thereby raising a nap on said ball.

100 14. In a device of the character described, 100 picking means for raising a nap on a tennis ball, means for repeatedly rolling a tennis ball into contact with said picking means, and means for continually shifting the axis of said rolling movement relative to the ball whereby all surfaces of the ball are affected by said picking means to raise a nap on the entire surface of the ball.

105 15. In a device of the character described, 110 a housing, means for continually picking the surface of a ball placed within the housing to raise a nap, said means serving to repeatedly pass the ball thru a circuitous path within the housing, and a member movable to a position to intercept movement of the ball thru said path.

115 16. In a device of the character described, 115 a housing adapted to receive a tennis ball, tracking means for the ball within the housing, means for repeatedly passing the ball over said tracking means, and means for raising a nap upon the surface of the ball as it passes over said tracking means.

120 17. In a device of the character described, 120 a housing adapted to receive a tennis ball, tracking means for the ball within the housing, means for repeatedly passing the ball over said tracking means, and means for

raising a nap upon the surface of the ball as it passes over said tracking means, said means including a plurality of spaced needle points, and means for resiliently supporting 5 said needle points.

18. In a device of the character described, a housing adapted to receive a tennis ball, resilient tracking means for the ball within the housing, means for repeatedly rolling the ball over said tracking means, and means 10 for raising a nap on the surface of the ball as it passes over said tracking means.

19. A method of reconditioning a tennis ball utilizing a plurality of needle points; 15 comprising causing the needle points to enter the ball cover, effecting relative lateral movement of the surface of the ball with respect to said needle points, and then withdrawing the ball from the needle points 20 whereby the needles pick a nap on the ball cover.

20. In a reconditioning device for tennis balls, picking means, and mechanical means for effecting a relative picking action between 25 said picking means and a tennis ball whereby a nap is produced on the surface of the ball.

21. In a reconditioning device for tennis balls, means for retaining a tennis ball, and 30 means for automatically raising a layer of nap on the ball and simultaneously enabling a chalk dust to be worked into the fiber on the surface of the ball.

22. In a reconditioning device for tennis 35 balls, a plurality of needle points, means for supporting said needle points, and means for effecting relative motion between said needle points and a tennis ball, said motion being such that the needle points are caused to enter the surface of the ball, are moved relative to its surface while in such engagement, and are then moved away from its surface, thus raising a nap on the surface of the ball.

45 23. In a reconditioning device for tennis balls, a plurality of needles, means for supporting said needles, and means for engaging a tennis ball for successively impaling each portion of the surface of the same on said needles, and for moving the surface so impaled back and away from said needles to produce a nap thereon.

24. In a reconditioning device for tennis 50 balls, a housing, a pair of curved tracks within said housing, needles disposed between said tracks, means for supporting said needles, and means for rolling a tennis ball along said tracks whereby the surface of the ball is brought in contact with said needles, thereby forming a nap on the surface of the ball.

55 25. In a reconditioning device for tennis balls, a housing, a pair of curved tracks supported within said housing, a plurality 60 of needles disposed between said tracks, a

belt for supporting said needles, and means for rolling a tennis ball along said tracks with its surface contacting with said needles, whereby a nap is formed on the surface of the ball, said means comprising a rotatable 70 drum journaled within said housing.

26. In a reconditioning device for tennis 75 balls, a housing, a pair of parallel curved tracks supported within said housing, a plurality of needles disposed between said tracks, a belt for supporting said needles, and means for traversing a tennis ball over said tracks with its surface engaging the points of said needles, thereby forming a nap on the surface of the ball, said means 80 including a rotatable drum journaled within said housing and means for preventing two balls within the housing from blocking each other's entrance upon said tracks.

27. In a reconditioning device for tennis 85 balls, a housing adapted to receive a tennis ball, a pair of parallel curved tracks resiliently supported within said housing, a plurality of needles disposed between said tracks, a flexible belt supporting said needles, a peripherally recessed rotatable drum 90 journaled within said housing whereby a tennis ball in the housing is repeatedly passed over the track in contact with the periphery of the drum to bring a peripheral 95 portion of the surface of the ball in engagement with the points of said needles, and means within said housing for causing different peripheral surfaces of the balls to be exposed to the picking action of said needles 100 for each passage of a ball over the track, thereby forming a nap on the surface of the ball.

28. In a reconditioning device for tennis 105 balls, a housing provided with an entrance opening for a tennis ball, a pair of spaced parallel tracks resiliently supported within said housing, a plurality of pointed needles disposed between said track, a belt serving to support said needles, means for repeatedly passing a tennis ball within the housing over said tracks comprising a rotatable drum journaled within said housing in spaced relationship with said tracks, an idler wheel journaled within said housing and 110 driven by said drum, said idler wheel serving to prevent locking of two balls within the housing, and means for turning a ball about an axis at an angle to its axis of rotation while passing over said tracks, as the 115 ball leaves said tracks, passage of a ball over said tracks serving to cause said needles to raise a nap on the surface of the ball.

In testimony whereof, I have hereunto set my hand.

ROBERT H. SMILIE.
